MAX LEZIUS, OF CLEVELAND, OHIO.

AUTOMATIC DAMPER FOR STOVES AND FURNACES.

1,272,064.

Specification of Letters Patent. Patented July 9, 1918.

Application filed November 30, 1914. Serial No. 874,694.

To all whom it may concern:

Be it known that I, MAX LEZIUS, a citizen of the United States, residing at Cleveland, in the county of Cuyahoga and State of Ohio, have invented certain new and useful Improvements in Automatic Dampers for Stoves and Furnaces, of which the following is a specification.

This invention relates to automatic dampers for stoves and furnaces, and the invention consists in a damper constructed and arranged substantially as hereinafter shown and described and more particularly pointed out in the claims.

The object of the invention is to provide a double damper arrangement for the discharge flue or pipe of a stove or furnace, especially a gas stove or furnace, whereby down-drafts will be automatically checked and up-drafts automatically regulated by the influence of drafts in opposite directions within the flue or pipe. A further object is to provide a separate article of manufacture and sale, comprising a balanced damper and ring adapted to make slip engagement with the inside of stove pipes of standard size.

In the accompanying drawings, Figure 1 is a sectional view longitudinally of my improved damper arrangement affixed to portions of a stove-pipe, and Fig. 2 is a side elevation thereof. Fig. 3 is a similar view to Fig. 1, but showing the relative positions of the two dampers under the influence of a down-draft. Fig. 4 is a cross section on line 4-4, Fig. 1. Fig. 5 is a reduced view in diagram of a triple arrangement of damper devices.

Fig. 6 is a sectional view of a damper and its supporting ring, and Fig. 7 is a side elevation thereof. Fig. 8 is a perspective view of one of the two annuli comprising the ring support for the damper plate and Fig. 9 is a side view of the damper plate alone. Fig. 10 is a side view of the journal pin for the damper plate.

In installing a gas stove or furnace, the only provision generally afforded to regulate the draft is by a hand-controlled damper. The difficulty of maintaining a proper draft under the constantly changing conditions which prevail in such an installation is obvious. Moreover, different types of stoves and furnaces, and radically different pipe and flue lengths, require different damper arrangements and settings to afford

proper regulation of the drafts, perfect combustion at the burner, and a uniform and economical distribution of the heat units. I have discovered that the necessary requirements may be met in a simple way by the use of a pair of damper devices which are adapted to operate automatically and which are particularly constructed to be adjustably affixed in any desired working relation in the ordinary or standard pipe or fitting for the discharge flue of a gas stove or furnace. These pipes or fittings are of standard size, and my invention involves the employment of a ring-shaped support 2 for a round flat damper plate 3, the said support being of a predetermined diameter externally to make a snug and slidable fit with the interior round wall of a standard pipe or fitting 4. A T-shaped fitting is generally used, and one damper device A is placed in the main passage 6, and a second damper device B is slidably and adjustably inserted within the side extension 7 of the pipe or fitting. Both damper devices are substantially the same in construction and the same reference characters are herein applied to designate like parts. Thus, the ring or support 2 comprises two annular members 8 each made of sheet metal bent at right angles 85 transversely to provide an inturned flange 9 having a series of notches 10 and lugs or projections 11 at the edge thereof. The two members 8 are placed with their respective flanges 9 in facial engagement and the lugs 11 are bent or doubled over the adjacent flange at the notches 10 to fasten the two members securely together. Each flange 9 is also provided with a pair of semi-circular channels or depressions 12 oppositely on a straight line joining the extremities of a short arc of the flange circle, and such channels or depressions provide divided boxes or bearings for the rounded ends 14 of a damper plate journal pin 15 when the two members 8 are fastened together with the pin in place therein. The damper plate 3 has reversely struck-up loop portions 16 to provide seating channels and confining loops for the journal pin 15, and the plate is locked 100 upon the pin by indents 17 in portions 16 opposite the annular grooves 18 in the pin.

Damper plate 3 is also provided with a pair of segmental weights 19, one at each side thereof, which conform to the smaller 110 segmental portion of the plate as divided by the pin or axis for the plate, and these

weights practically counterbalance the heavier segmental portion and larger divisional area 20 of the plate. The aim is to pivotally support the damper plate sufficiently at one side of its diameter, so that it will always come to a closed position automatically in line with the inturned flanges 9, and the counterweights 19 are intended to make the movement of the plate very sensitive to drafts from either direction. The ball ends of pin 15 minimize the friction and assure a free and sensitive movement of the damper plate and there is also a slight end play allowed to prevent any bind between the parts due to expansion of the pin under high temperatures. A fixed limit of movement of the damper plate is obtained by a lip or pair of lips 22 which are bent inward from the annular rim portion of one of the members 8 at a point adjacent or near the ends of the journal pin 15. One or more of the lugs 11 may also be bent inward to serve as a stop or as stops for the damper plate 3 when in a closed position, and this arrangement is used more often when the damper device is installed in a longitudinal position in a vertical pipe to positively check a down-draft.

In Figs. 1 to 3, two such damper devices as described are shown in co-acting relations. The damper device A is located in a horizontal position in the discharge end of the main or vertical pipe at a point slightly above the side extension which contains the second damper device B arranged in a perpendicular position more or less removed from the longitudinal axis of the vertical pipe. Device A may be moved downward or upward, more or less, and device B may be moved inward or outward, more or less, and their remoteness or nearness to one another is dependent upon the degree or amount of draft desired and the automatic regulation thereof. By moving the device B inward, its damper plate 3 can be made to swing into the vertical pipe more or less and by moving the device A downward, the respective plates 3 of both devices may be placed in overlapping relations according to any need or demand of a particular type of stove or furnace or of the draft conditions at the place of installation.

Under normal conditions, the damper device A is held in a full open position by the up-draft in the vertical pipe, say as shown in Fig. 1, and the damper device B is also held partly open by the up-draft; see full lines Fig. 1. The damper plate 3 of device B is inclined inwardly at intermittent intervals under these conditions, and when a sudden or excessive up-draft occurs, the said damper plate will swing open still more to admit an ample supply of air and relieve the up-draft on the stove or furnace, thereby preventing any disturbance of proper com-

bustion at the gas burner and also wasteful discharge of the heat generated by the burner. The inward movement of the damper plate of device B also tends to shut off the up-draft through the vertical pipe, especially when the device is set far enough inward to cause the damper plate to project into the pipe, see dotted lines Fig. 1.

Upon a down-draft, damper device A closes, see Fig. 3, and damper device B opens to permit a temporary escape of the products of combustion, thereby preventing smothering effects at the gas burner. Such conditions are usually temporary and only a slight relief is necessary; therefore, the damper plate 3 of device B is permitted to swing outwardly only a short distance, the degree of movement thereof being fixed by the lip 22 which is flexible and adapted to be bent into different set positions relatively to the damper plate and its axis. The damper plate may also be permitted to swing absolutely free without stop or limit by pressing the lip 22 back and out of the way of the movable plate. If desired, the pipe and side extension may be provided with slots or openings 25 opposite the ends of the pivot pins for the damper plates whereby the bearings may be oiled by way of the more or less open joint between the two ring members 8. However, oiling is not resorted to under ordinary conditions as the longitudinal and rotative movement of the journal pins is free and under a minimum of friction due to the ball bearing effect of the rounded ends of the pin.

The pipe or fitting 4 may be placed either in a vertical or horizontal position, and when horizontal, either or both damper plates 3 may be arranged to swing on either a vertical or horizontal axis by rotatably adjusting their supporting rings within the pipe so as to bring about the desired result. These rings provide independent mountings whereby the dampers may be set in different positions relatively to the pipe and to each other.

In Fig. 5 I show a third damper device C in the direct outlet 26 for the furnace 27, and this triple arrangement of dampers is of advantage in automatically regulating direct and indirect travel of the outgoing products of combustion.

What I claim is—

1. A stove or furnace pipe having a side draft extension, in combination with separate damper plates pivotally mounted at one side of their diametrical centers within said pipe and said extension respectively on slideable supports, each plate being sensitively balanced for self-action and adapted to open and close more or less completely across the passage-way through the part in which the same is mounted under the influence of up and down drafts through said pipe.

2. A pipe fitting for stoves and furnaces having a main passage and a side opening thereto, a balanced damper plate pivotally supported at one side of its diametrical center within the said main passage to open and close automatically across said passage under the direct influence of drafts from opposite directions, and a damper plate pivotally supported at one side of its diametrical center within said side opening and balanced to open automatically under the influence of drafts from opposite directions, the said damper plates being free to move independently of each other and each plate having an inserted support on which the plate is pivoted.

3. A stove or furnace pipe having a main passage and a side opening thereto, a swinging damper having a supporting ring therefor slidably mounted within said side opening to set said damper in various adjusted relations to the said main passage.

4. A stove or furnace pipe having a main passage and a side opening thereto, in combination with a pair of independent self-acting dampers and separate supports for said dampers slidably mounted within said main passage and said side opening, respectively.

5. A stove or furnace pipe and a pivoted damper plate and a ring supporting the same within said pipe and rotatably and slidably engaged therein, whereby said damper and support may be moved back from the end of said pipe.

6. A stove or furnace pipe having a side opening and a pair of self-acting damper plates mounted in independent working relations within said pipe and opening respectively, and one of said damper plates mounted on a support slidable lengthwise in said pipe to establish different fixed working relations between the same and the damper in said opening.

7. A damper device comprising a pair of rings having inturned flanges mechanically united in facial engagement and a damper plate having a journal-pin rotatably con-

fined by channeled bearing portions between said rings.

8. A damper device comprising a pair of rings having inturned flanges united together in facial engagement, and a damper plate having a journal pin rotatably confined at its ends between said flanges.

9. A damper device comprising a pair of rings having projecting portions interlocked together, and a swinging damper plate having a journal pin mounted upon said rings on the chord of an arc and in the meeting plane thereof.

10. A damper attachment for stoves and furnaces comprising a pair of flanged rings having notches and projections to fasten said rings together in facial engagement, and a damper plate having a journal pin rotatably confined between said flanged rings on the chord of an arc of said rings.

11. A damper attachment for stoves and furnaces, comprising a pair of attached rings having annular inturned flanges provided with semi-circular depressions oppositely related on a straight line joining the extremities of a short arc of the flange annulus, and a counterweighted damper plate having a journal pin with rounded ends mounted within said depressions between said rings.

12. A damper mechanism for stoves and furnaces, comprising a pipe having three open extremities, a balanced damper plate pivotally supported in one of said extremities to swing open under the influence of a draft from either direction, and a damper-plate pivoted within another extremity and weighted to open automatically and adapted to be closed under the influence of a back draft, said damper plates being free to operate independently in their respective positions.

In testimony whereof I affix my signature in presence of two witnesses.

MAX LEZIUS.
